UNITED STATES PATENT OFFICE

166,954

COMBINATION LOVE SEAT, LOUNGE,
AND BED

Robert N. Eisendrath, Chicago, Ill.

Application February 23, 1952, Serial No. 18,646

Term of patent 14 years

(Cl. D15—11)

To all whom it may concern:

Be it known that I, Robert N. Eisendrath, a citizen of the United States, residing at Chicago, in the county of Cook and State of Illinois, have invented a new, original, and ornamental Design for a Combination Love Seat, Lounge, and Bed, of which the following is a specification, reference being had to the accompanying drawing, forming a part thereof.

Fig. 1 is a front perspective view of a combination love seat, lounge, and bed embodying my new design with the ends thereof shown in upright position to form a love seat;

Fig. 2 is a perspective view similar to Fig. 1 with the ends partially lowered;

Fig. 3 is a perspective view similar to Fig. 1 with one end partially lowered and the other end completely lowered to form a lounge;

Fig. 4 is a perspective view similar to Fig. 1 with both ends in lowered position to form a bed;

Fig. 5 is a top plan view of the device shown in Fig. 4, and

Fig. 6 is an end elevational view of the ends shown in Fig. 4.

The dotted lines shown in the drawing are for illustrative purposes only.

I claim:

The ornamental design for a combination love seat, lounge, and bed, substantially as shown and described.

ROBERT N. EISENDRATH.
